UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

WIRELESS SIGNALING SYSTEM.

1,273,789.

Specification of Letters Patent. Patented July 23, 1918.

Application filed March 2, 1915. Serial No. 11,473.

To all whom it may concern:

Be it known that I, WILLIAM C. WHITE, a citizen of the United States, residing at Schenectady, in the county of Schenectady, 5 State of New York, have invented certain new and useful Improvements in Wireless Signaling Systems, of which the following is a specification.

My present invention relates to signaling 10 systems, and more especially to means for controlling the transmission of wireless signals.

The object of my invention is to provide an improved means for modulating or varying 15 the amplitude of continuous electrical waves, and especially for varying the amplitude of such waves in accordance with variations in sound waves.

In carrying my invention into effect I 20 prefer to employ an electron discharge device for producing continuous electrical waves in an antenna. The amplitude of the waves thus produced is controlled by a second electron discharge device operatively 25 connected to the first and having associated therewith a telephone transmitter or other suitable device for varying the potential of a controlling grid in said second electron discharge device. By thus varying the 30 potential of the grid in the second device the amplitude of the waves produced in the antenna may be efficiently varied as desired as will be more fully set forth hereinafter.

The novel features of my invention are 35 set forth with particularity in the appended claims. The invention itself however with further objects and advantages will best be understood by reference to the following description taken in connection with the 40 accompanying drawing in which I have illustrated diagrammatically the preferred embodiment of my invention.

As here indicated the means for producing 45 continuous waves in the antenna 1 comprises an electron discharge device 2 consisting of a highly evacuated envelop having therein a cathode 3 of filamentary form provided with a source of energy 4 for heating it to incandescence, an anode 5 and a 50 conducting body 6, which is preferably in the form of a grid interposed between the cathode and anode. The cathode and anode are connected respectively to conductors 8 and 7 which in turn are connected to a 55 source of direct current of the desired

potential. The circuit which includes the cathode and anode also contains an inductance 9 which is inductively related to the inductance 10 in the antenna, and also to an inductance 11 which is connected between 60 the cathode and the controlling grid 6. The coupling between 9 and 10 is preferably close while that between 9 and 11 may in some cases be made very loose. The inductance 11 is preferably shunted by a 65 variable condenser 12 and a battery 13 may be employed for adjusting the normal potential of the grid 6 to a value which is most suitable for the efficient operation of the device. The circuit consisting of the 70 direct current source of supply, the inductance 9, the cathode 3 and anode 5, for convenience of description, I designate as the plate circuit. The circuit which comprises the grid 6, the inductance 11 and the 75 cathode 3 I designate the grid circuit. With the arrangement described, when current starts to flow in the plate circuit a potential is induced in the coil 11 which varies the potential of the controlling grid 6. This 80 change in the grid potential in turn produces a variation in the current in the plate circuit. When the potential induced in the grid circuit causes the grid to become more negative the current flowing in the plate 85 circuit is decreased while an induced potential which makes the grid more positive increases the current flow in the plate circuit. These variations in the current in the plate circuit produce an alternating current in 90 the antenna and by varying the natural frequency of the grid circuit by varying the condenser 12 the frequency of the alternating current thus produced may be varied at will. It will of course be understood that 95 for the most efficient results the frequency of the current so produced should be substantially the same as the frequency to which the antenna is tuned. When the system thus far described is started in operation there will be produced in the antenna continuous electrical waves of practically 100 constant amplitude. The amplitude of these waves will depend to a large extent upon the amplitude of the potential variations in the 105 grid circuit. In order to utilize such waves for transmission of wireless signals it is necessary to either interrupt their continuity or vary their amplitude without interrupting their continuity. If it is desired to 110

transmit sound waves the amplitude of the continuous waves may be varied in accordance with the variations in the sound waves which it is desired to transmit. In order 5 to vary the amplitude of these continuous waves in accordance with variations in sound waves I employ a second electron discharge device 13', the cathode 14 and the anode 15 of which are connected respectively to the cathode 3 and the grid 6 of the first device. The battery 4 which serves to heat the cathode 3 to incandescence may also be employed for heating the cathode 14. The circuit of the controlling grid 16 of 10 this second device includes the secondary 17 of a transformer, the circuit of the primary 18 of which includes the telephone transmitter 19 and local battery 20. A battery 21 may also be inserted in the grid circuit 15 of this second device to adjust the normal potential of the controlling grid to the desired value.

In the system I have described very little current will flow in the grid circuit of the 25 first electron discharge device. As long as the second device is not connected to the grid circuit of the first device this grid circuit will oscillate freely and the oscillations therein will have a substantially constant 30 amplitude. As soon however as the second device 13' is connected to the grid circuit of the first device and current is allowed to flow through the second device, energy will be diverted from the grid circuit of the first 35 device and the oscillations set up therein will be heavily damped, the amount of the damping of the oscillations of course depending upon the amount of energy withdrawn from the grid circuit. The amount 40 of energy thus withdrawn will vary in accordance with the variations in the potential of the controlling grid 16 which variations may be produced by the action of sound waves in the telephone transmitter 19. 45 Hence it will be seen that in the system I have described the amplitude of the electrical waves produced in the antenna 1 will vary in accordance with the variations in sound waves acting upon the telephone 50 transmitter 19.

When the electron discharge device 13' is connected as described across the grid circuit of the device 2 the frequency of the grid circuit is dependent to a certain extent 55 upon the resistance of the electron discharge device 13', and since a variation in the potential of the grid 16 varies this resistance the frequency of the grid circuit of the device 2 will also be varied. This will result 60 in a variation in the frequency of the waves produced and hence will tend to vary the frequency of the waves radiated from the antenna. In some cases this additional controlling effect may become so great that the

articulation of the speech waves transmitted 65 will be impaired. In order to prevent such an impairment in the articulation it may be found desirable to employ a resistance 22 in series with the electron discharge device 13' in order to reduce the variation in the 70 frequency of the grid circuit of the device 2 with variations in the resistance of the device 13'. I also find it desirable to employ a condenser 23 in shunt across the supply conductors 7 and 8 in order that the high 75 frequency component of the current in the plate circuit of the device 2 will not be required to pass through the supply source.

While the system which I have illustrated and described is the preferred embodiment 80 of my invention I do not wish to be limited to this specific arrangement as it will be apparent to one skilled in the art that many variations therein may be made without departing from the scope of the appended 85 claims.

What I claim as new and desire to secure by Letters Patent of the United States is:—

1. The combination in a wireless signaling system of an antenna, means comprising an 90 electron discharge device having a cathode, an anode and a controlling grid for producing oscillations in said antenna and a second electron discharge device directly connected to the grid circuit of the first electron 95 discharge device and supplied with energy therefrom to control the amplitude and frequency of the oscillations set up in said antenna.

2. The combination in a wireless signaling 100 system of an antenna, an electron discharge device comprising a cathode, an anode and a controlling grid operatively related to said antenna and arranged to produce continuous electrical waves therein, a second electron 105 discharge device connected to the grid circuit of the first device to divert energy therefrom and means for varying the amount of energy thus diverted.

3. The combination in a wireless signaling 110 system of an antenna, an electron discharge device comprising a cathode, an anode and a controlling grid operatively related to said antenna and arranged to produce continuous electrical waves therein, a 115 second electron discharge device having a cathode, an anode and a controlling grid, the cathode and anode of the second device being connected respectively to the cathode and grid of the first device and means for 120 varying the potential of the grid in the second device.

4. The combination in a wireless signaling 125 system of an antenna, an electron discharge device having a cathode, an anode, and a controlling grid, the plate circuit of said electron discharge device being inductively related to said antenna, a source of energy

in the plate circuit of said electron discharge device, means for varying the potential of the controlling grid to vary the current flowing through said electron discharge device, a second electron discharge device similar to the first connected to the grid circuit of the first electron discharge device in such a way as to divert energy therefrom and means for varying the potential of the controlling grid in said second device.

5. The combination in a wireless signaling system of an antenna, an electron discharge device, comprising a cathode, an anode and a controlling grid, operatively related to said antenna and arranged to produce continuous electrical waves therein, a second electron discharge device similar to the first connected to the grid circuit of the first in such a way as to divert energy therefrom 15 and means for varying the potential of the controlling grid in said second device.

6. The combination in a wireless telephone system of an antenna, an electron discharge device, comprising a cathode, an anode and 25 a controlling grid, operatively related to said antenna and arranged to produce continuous electrical waves therein, a second electron discharge device similar to the first connected to the grid circuit of the first in such a way as to divert energy therefrom 30 and means comprising a telephone transmitter for varying the potential of the controlling grid in said second device.

7. The combination in a wireless signaling system of an antenna, an electron discharge device comprising a cathode, an anode and a controlling grid operatively related to said antenna and arranged to produce continuous electrical waves therein and 35 means connected to the grid circuit of said device in such a way as to divert energy therefrom and to simultaneously vary the amplitude and frequency of the waves thus produced.

40 8. The combination in a wireless signaling system of an antenna, an electron discharge device comprising a cathode, an anode and a controlling grid operatively related to said antenna and arranged to produce continuous electrical waves therein, a second electron discharge device connected to the grid circuit of the first device to divert energy therefrom, and means for varying the amount of energy thus diverted 45 in accordance with the variations in sound waves.

9. The combination in a wireless signaling system of an antenna, an electron discharge device comprising a cathode, an anode and 50 a controlling grid for producing continuous electrical waves in said antenna, a second electron discharge device similar to the first and having its cathode and anode connected respectively to the cathode and grid of the

first device, and means for varying the potential of the grid in the second device in accordance with the variations in sound waves.

10. The combination in a wireless signaling system of an antenna, an electron discharge device comprising a cathode, an anode and a controlling grid operatively related to said antenna and arranged to produce continuous electrical waves therein, and means connected to the grid circuit of said device to divert a variable amount of energy therefrom and thereby vary the amplitude of the waves thus produced in accordance with the variations in sound waves.

11. The method of wireless signaling by means of a system in which continuous electrical waves are produced in an antenna by an electron discharge device comprising a cathode, an anode and a controlling grid, which consists in varying the amplitude of the waves thus produced by diverting a variable amount of energy from the grid circuit of the electron discharge device in accordance with signals to be transmitted.

12. The method of wireless signaling by means of a system in which continuous electrical waves are produced in an antenna by an electron discharge device comprising a cathode, an anode and a controlling grid, which consists in controlling the amplitude and frequency of the waves thus produced by diverting energy from the grid circuit of the electron discharge device in accordance with signals to be transmitted.

13. The method of wireless signaling by means of a system in which continuous electrical waves are produced in an antenna by means of an electron discharge device comprising a cathode, an anode and a controlling grid, which consists in diverting energy from the grid circuit of the electron discharge device, and varying the amount of energy thus diverted in accordance with variations in sound waves.

14. The method of transmitting signals in a system comprising two electron discharge devices each having a cathode, an anode and a controlling grid, and in which one of the electron discharge devices is utilized for producing continuous electrical waves, which consists in diverting energy from the grid circuit of the electron discharge device which produces the continuous electrical waves, to the plate circuit of the other device, varying the amount of energy diverted by varying the potential of the grid of the second device in accordance with the signals to be transmitted and thereby producing a corresponding variation in the amplitude of the waves produced by the first device.

15. The method of modulating continuous electrical waves produced by means of an electron discharge device comprising a cath-

ode, an anode and a controlling grid which consists in diverting energy from the grid circuit of the electron discharge device and varying the amount of energy thus diverted 5 in accordance with variations in a modulating current.

16. Means for producing modulated continuous electrical waves comprising an electron discharge device having a cathode, an 10 anode, and a controlling grid, plate and grid circuits for said device so arranged that con-

tinuous electrical waves will be produced therein, means for diverting energy from the grid circuit and means for varying the amount of energy diverted in accordance with 15 variations in a modulating current.

In witness whereof, I have hereunto set my hand this 1st day of March, 1915.

WILLIAM C. WHITE.
